UNITED STATES PATENT OFFICE.

SAMUEL D. PAGE, OF DES MOINES, IOWA.

COVER FOR AUCTION-SALES RECORDS AND THE LIKE.

1,345,329.

Specification of Letters Patent. Patented June 29, 1920.

Application filed May 6, 1918, Serial No. 232,976. Renewed April 3, 1920. Serial No. 371,140.

To all whom it may concern:

Be it known that I, SAMUEL D. PAGE, a citizen of the United States, and resident of Des Moines, in the county of Polk and State 5 of Iowa, have invented a certain new and useful Cover for Auction-Sales Records and the like, of which the following is a specification.

The object of my invention is to provide a 10 cover for auction sales records and the like, of simple and inexpensive construction, particularly adapted for use at auction sales and other places where it is necessary to use a number of sheets of paper in making records 15 where it is necessary to protect part of the sheets while others are being used.

A further object is to provide such a cover having means for holding blank sheets of paper, and to provide an auxiliary binder 20 connected by a flexible hinge, having one member adapted to be secured to the cover, and provided with a slot to receive a stiff member on a pad of statement sheets.

Still a further object is to provide such a 25 cover having on another member a pocket to receive a stiff member on the pad of sheets, and having the stiff sheet connected with the cover by a flexible hinge and adapted to protect the last named pad of sheets.

30 With these and other objects in view, my invention consists in the construction, arrangement and combination of the various parts of the device, whereby the objects contemplated are attained, as hereinafter more 35 fully set forth, pointed out in my claim, and illustrated in the accompanying drawings, in which:

Figure 1 shows a top or plan view of the 40 cover in its open position, parts being broken away to better illustrate the construction.

Fig. 2 shows a sectional view, taken on the line 2—2 of Fig. 1.

Fig. 3 shows a side view of one of the cover members having receiving pockets thereon, 45 showing the auxiliary binder secured thereto, and holding a pad of statement sheets.

Fig. 4 shows a sectional view, taken on the line 4—4 of Fig. 3.

Fig. 5 shows an enlarged, detail, sectional 50 view of one of the sheets of paper with the carbon or duplicating material on the back thereof.

Fig. 6 shows a sectional view, taken on the line 6—6 of Fig. 1, and

55 Fig. 7 shows a sectional view, taken on the line 7—7 of Fig. 1.

In the accompanying drawings I have used the reference numerals 10 and 11 to indicate generally the opposite members of my improved cover, which are connected by a 60 flexible hinge or binder member 12, which is of such width as to permit the cover members 10 and 11 to be folded over on each other with considerable material received between them.

65 The cover member 10 is provided on its inner surface near its corners, with four triangular pockets 13. These pockets are designed to receive blank sheets of paper 14, which may be used for any desired purpose.

I preferably use in connection with the 70 cover member 10, a binder comprising a bottom sheet or member 15 of comparatively stiff material, and a top sheet 16 of comparatively stiff material, said sheets being connected along adjacent side edges by means of a flexible binder 17. The binder member 15 is provided near its upper edge with a horizontal slot 18. The binder member 15 is of such size that its corners may be inserted into the pockets 13 for supporting and holding the binder in the cover.

75 The binder is designed to hold a pad of sheets, which pad is indicated generally by the reference character A. These sheets may 80 consist of a number of sheets 19, having adjacent to one edge index characters 20, and a number of statement sheets above the sheets 19. Each of the statement sheets is preferably divided into a number of parts 21, each 85 of which parts is adapted to comprise a blank for a statement. The statement sheets are provided with perforations for dividing the said sheets into the portions 21, the perforations being indicated by the reference 90 character 22.

95 The pad of sheets A is bound together in any suitable way, and has at its back a stiff tongue or the like 23, shown in Fig. 4, adapted to be extended through the slot 18, 100 as illustrated in said figure.

In the practical use of that portion of my 105 invention which has already been described, it will be seen that the cover members 10 and 11 may be opened and folded over against each other, with the inner surface of the cover member 10 up. The binder member 16 may then be folded over for exposing the top statement sheet. A statement showing the sale, including the article sold, the price 110 and the name of the purchaser, may be made out on one of the portions or sections 21, and

such section may then be torn off along the perforated lines and handed to the purchaser. The statement sheets, one of which is shown in Fig. 5, are provided on the back with suitable carbon or reproducing material 24.

In this connection, it may be mentioned that in making out a statement, the binder member 16 may be folded underneath the 10 two upper statement sheets, so that the carbon reproduction of anything written on the top sheet will be made on the second sheet, but no impression will be made through the member 16 on the underlying 15 statement sheets, and only the two upper statement sheets will be exposed to drafts of air where the work is being done.

At the upper end of the cover member 11 on the inner surface thereof, there is provided a pocket 25 open at its upper end. I provide for use with the cover member 11, a pad indicated generally by the reference character B, made up of sheets which may be ruled, as shown in Fig. 1, for listing the 20 articles sold. The sheets of the pad B are provided with carbon backs, as are the statement sheets.

It may be mentioned in this connection that the carbon backs may be provided only 30 on the alternate sheets of the statement sheets and the listing sheets above described.

The sheets of the pad B are bound together in any suitable way, and the back of the pad is provided with a stiff tongue 35 26, shown in Fig. 7, adapted to slip into the pocket 25.

Secured to the cover member 11 by means 40 of the flexible binder 27, is a stiff leaf 28, adapted to cover the pad B when it is not in use and to be placed under the first two sheets thereof when the first or top pair of sheets are being used.

In the practical use of my improved cover 45 for auction sales records and the like, when a sale is being conducted the portion 10 with the binder secured thereto, is folded over under the member 11, and the stiff leaf 28 is preferably placed under the uppermost 50 pair of sheets of the pad B. The member 16 of the binder will hold the sheets of the pad A from being blown about by the wind. The article sold, the name of the purchaser and the purchase price and terms, are put down on the sheets of the pad B as the 55 transactions occur. If the purchaser desires a statement at once, the cover is thrown over until the member 10 is up. The stiff leaf 28 is placed on the outside of the pad B, so

as to protect its sheets from the wind; the binder member 16 is placed under the two 60 top sheets of the statement pad A, and a statement is written out for the purchaser, torn off and handed to him. A copy of the statement will be left on the second sheet beneath the top sheet of the statement pad. 65

Attention is called to the convenience in handling my improved sales cover, whereby the various sheets may be held against being blown about by the wind at all times.

If it is desired to use extra paper for 70 scratch paper or the like, the binder may be quickly and easily removed from the pockets 13, and some of the sheets 14 may be taken out.

It will be seen that the pads A and B may 75 be quickly and easily replaced whenever desired, but that the cover is practically permanent and may be used with a large number of said pads.

It will be obvious that my improved cover 80 for auction sales records and the like, with its various parts, may be put to a great variety of uses, and that some changes may be made in the construction and arrangement of the parts, without departing from the 85 essential intent and purposes of my invention, and it is my intention to cover by my present claims, any modified forms of structure or use of mechanical equivalents which may be reasonably included within the scope 90 of my claim.

I claim as my invention:

In a device of the class described, a cover comprising cover members having a flexible connection along one side edge, one of said 95 cover members having on the inside a plurality of pockets, a binder comprising a pair of cover members having a flexible connection along one side edge, one of the binder cover members being received in said pockets and having adjacent to one end a transverse slot, a pad of sheets connected at one end, said pad having adjacent to said end a stiff back member provided with a tongue 100 received in said slot, whereby the pad sheets 105 are connected at one end, and the binder cover members are connected at one side edge to permit a binder cover member to cover the pad, or to be inserted between the sheets 110 of the pad, and whereby when such binder member is inserted between the sheets of the pad, the members of the cover may be folded over for covering the pad.

Des Moines, Iowa, January 31, 1918.

SAMUEL D. PAGE.
